UNITED STATES PATENT OFFICE

157,321

COMBINATION REAR BUMPER, TRAILER HITCH, AND FOOT PLATFORM FOR VE- HICLES

Carl G. Barden, Woodland, Calif.

Application January 11, 1949, Serial No. 162

Term of patent 14 years

(Cl. D14—6)

To all whom it may concern:

Be it known that I, Carl G. Barden, a citizen of the United States, residing at Woodland, in the county of Yolo and State of California, have invented a new, original, and ornamental Design for Combination Rear Bumper, Trailer Hitch and Foot Platform For Vehicles, of which the following is a specification, reference being had to the accompanying drawing, forming a part thereof.

Fig. 1 is a perspective view of a combination rear bumper, trailer hitch and foot platform for vehicles, looking toward the outer end and one side thereof and showing my new design; the opposite side of the device presenting the same appearance.

Fig. 2 is a cross sectional view on line 2—2 of Fig. 1.

Fig. 3 is a similar view on line 3—3 of Fig. 1. The dotted partial outline of a vehicle in Fig. 1 is for illustrative purposes only.

I claim:

The ornamental design for a combination rear bumper, trailer hitch and foot platform for vehicles, as shown, and described.

CARL G. BAR DEN.
